CALCULATING MACHINE

Harold T. Avery and Gustav Lerch, Oakland,
Calif., assignors to Marchant Calculating Ma-
chine Company, a corporation of California

Application July 15, 1931, Serial No. 550,855

4 Claims. (Cl. 235—79)

The present invention relates to calculating machines of the type adapted to perform the four cardinal calculations and combinations thereof, but particularly to the type embodying 5 means whereby multiplication and division operations are performed automatically.

Mechanism disclosed herein whereby the add key, the depression of which results in the release of all depressed keys of the keyboard at the end 10 of each cycle of operation, is automatically released from depressed position upon manipulation of the automatic division control member, is claimed in the copending divisional application of Harold T. Avery, Serial Number 727,709, filed 15 May 26, 1934.

An object of the invention is to provide means whereby the machine will be arrested and the automatic division control member released at the end of the first denominational order as a 20 warning to the operator in the event that the machine has been set to register a complementary quotient.

A further object of the invention is to provide means whereby the operator may purposely obtain registration of a complementary quotient by holding the automatic division control member in operative position.

Other objects will appear as this description progresses.

The invention possesses a plurality of advantageous features, some of which will be set forth at length in the following description where that form of the invention which has been selected for illustration in the drawings accompanying 35 and forming a part of the present specification, will be described in full. In said drawings the preferred form of the apparatus has been shown, but it is to be understood that the invention has not been limited to such form, since the invention 40 as set forth in the claims may be embodied in a plurality of other forms.

It is manifest that the invention may be embodied in any calculating machine of the type mentioned above. However, in the accompanying drawings, it is shown embodied in a motor driven machine of the general type disclosed in the patent to Friden, Number 1,643,710, dated September 27th, 1927, but is an improvement on the machine disclosed in the application of Avery and Lerch, Number 405,127, dated November 6th, 1929, to which reference is hereby made for a disclosure of mechanisms as are not specifically described herein.

In the drawings accompanying and forming a 55 part of the present specification:

Figure 1 is a longitudinal section from the left, showing drive and power control mechanisms.

Figure 2 is a longitudinal section from the right, showing the plus and minus bar structures.

Figure 3 is a lateral section from the rear, showing the reverse mechanism and the automatic division control therefor.

Figure 4 is a section taken on line 4—4 of Figure 3, showing a mechanism for preventing a reversing operation in half cycle position.

Figure 5 is a lateral section from the front showing the automatic carriage shifting mechanism.

Figures 6, 6A, and 7 are details of the shift clutch control.

Figure 8 is an assembly view of the clearing and shift control.

Figure 9 is a detail of the clear and shift key interlocking mechanism.

Figure 10 is a longitudinal section of the automatic multiplier unit showing the automatic shift control.

Figure 10A is a plan view of the add key releasing mechanism and a portion of the automatic division control means.

Figure 11 is a section from the left showing the automatic division control lever and associated mechanism.

Figure 12 is a section showing certain of the division controls.

Figures 13 to 16 are details of portions of the mechanism shown in Figure 12.

Figure 17 is an elevation of the automatic carriage shifting mechanism.

Figure 18 is a plan view of details of the automatic carriage shifting mechanism.

Figures 19 and 20 are also details of the automatic carriage shifting mechanism.

Figures 21 and 22 are diagrammatic views showing the drive gear trains to the various mechanisms.

Calculating machines are provided with means whereby it is necessary to make a manual setting to obtain registration of true multipliers during the performance of automatic multiplication and 45 true quotients during the performance of automatic division. This same manual setting makes it possible for the operator to obtain complementary multipliers and quotients if the nature of the calculation requires them. It is obvious, 50 then, that during successive problems in multiplication and division, inadvertence or undue speed on the part of the operator may result in overlooking this manual setting whereby a complementary quotient may be obtained when a true 55

- quotient is desired. In some cases the difference between a complementary and true quotient may be so slight that the mistake would not be noticed by the operator. The present invention provides means whereby the machine is stopped at the end of the first denominational order of the calculation if the machine is set to register a complementary quotient, thereby insuring the registration of the desired quotient figure.
- If, then, the registration of said complementary quotient is due to a faulty setting of the machine, it is only necessary for the operator to shift the carriage back to the first denominational order and depress the plus key, thereby rotating the actuator a sufficient number of times in the opposite direction to correct the factors of the calculation, instead of having to clear the accumulating and counter registers and again reset the entire group of factors into the machine.
- However, if the operator has purposely set the machine to register a complementary quotient, means have been provided, in conjunction with the present invention, whereby said complementary quotient may be obtained without this intermittent arresting of the machine between each denominational order. This is accomplished by the operator's holding the automatic division control lever in its forward operative position, and the means controlled thereby will be described in full hereinafter.

Calculating machines are ordinarily provided with an add key which, while maintained in its depressed position, causes the release of all depressed keys of the keyboard and may also limit the actuator to one full revolution for each depression of the plus and minus bars. Due to the construction and operation of this add key control mechanism, the performance of automatic division is impossible while said key is in its depressed position. In the machine disclosed herein, the release of said add key is automatically effected upon displacement of the automatic division control lever to its operative position. The construction of the mechanism accomplishing this end will be described in full hereinafter.

Actuator, accumulator, and counter

The calculating machine embodying the present invention comprises a reversible rotary actuator 380 (Figure 3) and a plurality of keys which, upon depression thereof, introduce into said actuator values corresponding to the numerals delineated thereon, and the rotation of said actuator serves to transfer these values to the numeral wheels of the accumulating register 400 (Figure 5) to effect the calculating operation. For the purpose of making direct action of the selected values on the numeral wheel of highest order possible, the accumulating register is disposed in parallel displaceable relation to the axis of the actuator.

The machine is also provided with a stationary counting register 375 (Figure 5) so arranged that it will count the number of rotations of the actuator in any denominational order positively or negatively.

Each of these registering mechanism is provided with suitable tens transfer means, as disclosed in the above-mentioned patent, and other associated mechanisms which will be described in full as the specification progresses.

Drive control

In the present embodiment the driving mechanism comprises an electric motor which is con-

nected to the drive shaft 100 (Figure 1) by appropriate reducing gearing, and is adapted to be intermittently connected to the calculating mechanism to drive the same.

The means whereby the drive is connected to the calculating mechanism includes a clutch 110, the driving member of which is a toothed wheel 111 fixed on one end of the drive shaft 100. Enclosing the toothed wheel 111 is a circular housing 112 which constitutes the driven member of the clutch, and pivoted within this housing, in a position to engage the toothed wheel 111, is a driving pawl 113. This pawl is normally pressed into engagement with the toothed wheel by means of the inset compression spring 114, but it is adapted to be maintained in its non-engaging position by means of the clutch control mechanism. The clutch control mechanism comprises a bell crank member 115 journaled on the stud shaft 116 on the machine frame, and carrying on one arm a foot 117 adapted, when the actuator is in full cycle position, to project through an appropriately positioned aperture in the clutch housing 112, to engage the tail of the pawl 113 and urge it to clutch disengaging position. A spring 118, tensioned between a stud on the machine base and the opposite arm of the bell crank 115, tends to urge the foot 117 into disengaging position, so that in the absence of intervention by other instrumentalities, the actuator will be brought to rest with the clutch in disengaged position when it reaches full cycle position after a rotation.

Means are provided for operating the bell crank 115 to engage the actuator for the number of rotations requisite to perform a desired calculation, and pin 119 is provided on the forward end of the bell crank for this purpose. Pin 119 is engaged by the notched rear end of the control link 121 which is pivoted at its forward end to control plate 120, and normally held in position overlying the pin 119 by spring 122 tensioned between the shaft 123 and an intermediate point on the control link. Control plate 120 is fixed to shaft 123 journaled in the machine and comprises a forward vertical portion 120B adapted to cooperate with the plus key and a rearward inclined portion 120A adapted to cooperate with the minus key. Operation of either of these keys serves to impart a counter-clockwise oscillation to control plate 120. This imparts corresponding counter-clockwise oscillation to the clutch operating bell crank 115, permitting engagement of the driving pawl 113 for the period that such adjustment is maintained. Means whereby the plus and minus keys accomplish this end will be described hereinafter.

Reversing gearing

Fixed to the clutch housing 110 (Figure 3) for rotation therewith, is a sleeve 130 journaled in an intermediate wall of the machine, and journaled upon this sleeve adjacent the clutch housing are two gears 131 and 132. On their contiguous faces, these gears are provided with annular flanges 133, each of which is provided with two oppositely disposed seats of different depth designed to receive pin 134 fixed in shifting shaft 135, and adapted to engage said seats through oppositely disposed orifices in the sleeve 130. A shifting of the pin 134, then, by means of the shaft 135, causes one or the other of the two gears to be engaged for drive by the clutch housing. One of these gears includes an intermediate idler 131A in its driving train to the 75

Plus and minus keys

actuator which the other omits, and they therefore serve to drive the actuator in opposite directions as shown diagrammatically in Figure 22. This portion of the mechanism is fully disclosed 5 in the patent to Friden Number 1,682,901 dated September 4, 1928. In Figure 3, the pin 134 is shown so positioned as to drive the actuator in the additive direction into which position it is normally urged by the spring 226 (Figure 2) supporting the minus bar.

Means are provided for shifting the shaft 135 (Figure 3) to carry the pin into engagement with the negative driving gear 132. This means is made resilient so that its control may be superseded by other controls operative in automatic division operations as will be hereinafter set forth. The shaft 135 carries a collar 140 which is inclosed by slidable sleeve 141 which also encloses a compression spring 142, one end of which 15 bears against the collar 140 and the other end of which bears against one end of the sleeve 141, thus maintaining the collar in engagement with the other end of said sleeve. The shifting fork shown in Friden Patent Number 1,643,710 engages this collar 141 as shown at 143 and lateral motion thereof tends to shift the shaft 135 and its pin 134 into engagement with either of the two driving gears selectively.

A study of the Friden Patent Number 1,682,901 will reveal that the pin shift reversing mechanism described can be shifted in full and half cycle position, and since an accidental shift in half cycle position, caused by depression of the minus key during a problem in automatic division, is undesirable, means have been provided whereby a shift in half cycle position is rendered impossible. This is accomplished by provision of a radial flange 160 (Figures 3 and 4) which is fixed to the shaft 135 and adapted to rotate therewith. This flange is provided with a wide slot 160A which, while the shaft 135 is in full cycle position, is in radial alignment with a depending tooth 162A of a bracket 162. This bracket 162 is rigidly secured to the shaft 161 which is merely a supporting bar between the frames of the machine. The relative position of the radial flange 160 and the depending tooth 162A is such that when the shaft 135 is shifted to one of its positions the flange 160 is disposed on one side of the tooth 162A and when the shaft is shifted to its other position, the flange is disposed on the other side of said tooth. The depending tooth 162A is of sufficient length so that the shift of the shaft 135 from one position to the other can only be made while the slot 160A of the flange is in radial alignment with the tooth 162A. This condition being fulfilled only at full cycle position, it is obvious that the shaft 135 and the reversing pin carried thereby can be shifted only at such time.

Since the accumulator and counter actuators must be necessarily arranged to rotate in the same direction or opposite directions from each other, a manually reversing means has been provided therebetween. This manual setting is accomplished through longitudinal movement of a lever 150 (Figure 3), which, through a worm cam provided on its lower extremity, slides a shaft 151 laterally. This displacement, through a fork 152, positions a gear 153 to operate either direct or through the idler gear 131A. This mechanism is fully disclosed in the Friden Patent 75 1,643,710.

Selectively operable, manual means are provided for controlling the engagement and direction of the drive. The means for manually controlling rotation in the forward direction comprises a plus key 208 (Figure 2) supported on a frame 201. This frame is supported on one end of a pair of parallel links 202 which are connected together at their opposite ends by a link 203 and are pivoted intermediate their ends to the plate 210. Tensioned spring 204 tends to hold the plus key in its elevated position. The frame 201 carries a roller 205 which extends through an aperture in the plate 210 and abuts the forward vertical end 120B of the control link 120 (Figures 1 and 2). Due to the manner in which the frame is mounted upon the parallel links, depression of the plus bar causes the roller to be moved downwardly and to the rear, rocking the control plate in a counter-clockwise direction to effect engagement of the main clutch in the manner hereinbefore set forth.

The manual means for controlling reverse engagement of the drive comprises a minus key 220, 25 slidably mounted on the intermediate plate 210 by means of a pin and slot connection 221. The stem of this key carries a pin 222 which extends through an opening in the intermediate plate and overlies the upper arm of a bell crank 223 pivoted at 224 to said intermediate frame 210 (Figure 2) on the opposite side thereof from said key. The key 220 is urged to its elevated positions by means of a spring 220B (Figure 1) cooperating with a pin 220A on the stem of said key. The upper 30 arm of said bell crank 223 is provided with a roller 225 which abuts the rearward inclined portion 120A of the control plate 120 and which is adapted upon depression of the key to rock the plate in a counter-clockwise direction, thereby effecting engagement of the main clutch. The lower arm of said bell crank is connected by a link 227 with a worm cam which controls the reversing gear as fully disclosed in the aforementioned patent to Friden Number 1,643,710. 40 Depression of the key 220, therefore, in addition to effecting engagement of the drive, operates the reversing gear to reverse the direction of the drive. To prevent concurrent depression of the plus and minus keys, an interlock is provided 45 comprising a bar 238 (Figure 2) pivoted on the intermediate plate between the two keys, and having one arm underlying the roller 205 of the plus key, while its other end underlies the upper arm of bell crank 223. Depression of either key 50 rocks the arm to prevent depression of the other key.

Add key

A special key 258 (Figure 10), designated as 60 the "add key", is provided to control the various mechanisms in the performance of addition. Said key 258 is pivoted at 251 to a lever 252 pivoted at 253 and normally held in its elevated position by a spring 256. The upper end of the key 65 stem is provided with a notch 255 adapted to engage the cover plate upon depression of said key to temporarily retain it in operative position. The spring 256, being angularly tensioned between the lower extremity of the key and a fixed 70 portion of the machine, also tends to rock the key into latching position.

The rear end of lever 252 is bifurcated and engages a pin 268 on a pitman 261 driven by the machine and operated, when raised into opera- 75

tive position by the depression of key 250, to release the keys by contacting the gate 254 near the end of each cycle of operation. The operation of this pitman in releasing the depressed keys is fully disclosed in the patent to Friden, Number 1,643,710, dated September 27th, 1927.

Depression of the key 250 also disables the automatic carriage shift mechanism through means which will be described hereinafter.

10 *Carriage shifting mechanism*

The accumulator carriage 400 (Figure 5) is slidably mounted on a trackway 500 under which is arranged mechanism for manually or automatically shifting this carriage in either direction. This carriage shifting mechanism includes a plate 502 pivoted at 501 and having a notch 503 in its upper end embracing a pin 504 which is moved laterally to shift the carriage by rocking the plate to one side of its pivot or the other.

For this purpose a link 550 is provided, adapted to be reciprocated in the appropriate direction by the driving motor. This link is designed to impart a quickly accelerated motion to the carriage through approximately the first half of its step of movement, whereupon the acquired momentum is sufficient to complete the shift. The construction which makes this possible has the additional advantage of permitting idle movement of the link in the event of a locking of the carriage mechanism, thus preventing a jam.

The link 550 is slidably mounted by pin and slot connection 551 and 552 to stationary portions of the machine and is provided adjacent plate 502 with a cut out portion through which pass pivot rod 501 and a pin 553 fixed to plate 502. Pivotedly mounted on link 550 at 554 are spring shift bars 555 abutting opposite sides of pin 553 and normally maintained vertical by compression springs 556 disposed between opposite anchors on link 550 and bars 555, pressing said bars against a lug 557 and 550.

The right end of link 550 is provided with notches 558 and 558A cooperating with peripheral cams 561 and 561A and driven by carriage shift clutches 562 and 562A, respectively, to reciprocate link 550 to the right or left, depending upon the clutch selected for operation. The peripheral cams 561 and 561A are provided with notches 558A and 558B (Figure 17), respectively, which underlie link 550 when the clutches are in full cycle position, permitting either cam to operate link 550 without interference from the other.

As the link 550 is reciprocated to the right or left by one of the cams, one of the springs 556 (Figure 5) is slightly compressed due to the inertia of the carriage and shifting mechanism, but as the carriage is started in motion, it expands, accelerating the carriage sufficiently to carry it a full step, although the link 550 moves only about a half step distance. In the event that the carriage is locked against movement the spring 556 will merely be farther compressed, as the bar 555 moves about its pivot 554 during reciprocation of link 550 and no jam will ensue.

The construction and operation of the two shift clutches, being substantially identical, only one will be described, except in touching on their differences. The cam 561, driven by clutch 562, shifts the carriage to the right and the shift clutch is controlled by key 570 (Figure 5), while cam 561A driven by clutch 562A shifts the carriage, to the left, and this clutch is controlled by key 570A. These keys are relatively arranged,

not with respect to the actual direction of the carriage shift, but with respect to the direction of denominational shift, as indicated by the usual pointer associated with the counter and which moves oppositely from the carriage. Operation of the right hand key 570A, therefore, moves the carriage into a lower denominational position, while operation of the left hand key 570 moves the carriage into a higher denominational position.

Both clutches are of the same pawl and ratchet type as the main clutch 110 heretofore described, and are mounted on and driven by shaft 563 geared to the main drive shaft 100. Clutch 562A is controlled by a clutch control lever 566A (Figure 6) corresponding to the main clutch control lever 115, shown in Figure 1. This shift control lever 566A is pivoted at 567 and has a hooked shaped upper end 568A adapted to be engaged by a pin 569A carried on the lower extremity 20 of the key 570A which key is pivoted at 571 and urged to its upward position by a spring 573A tensioned between an intermediate position on the key lever and a stud on the machine frame provided therefor. Both clutch control levers 25 are provided with tails 574 and 574A for automatic operation, as will be hereinafter described, and are provided with spring 575A urging them to clutch disengaging position.

30 *Automatic control of carriage shifting*

Automatic means are provided for engaging the carriage shift clutch at the proper time in automatic multiplication and automatic division operations. Automatic carriage shifting always 35 occurs at the end of an additive rotation of the actuator, in automatic multiplication immediately after the last successive addition in each denominational order, and in automatic division at the end of the additive rotation which corrects 40 the overdraft in each denominational order. The shift clutch releasing means is, therefore, arranged to be driven with the actuator in additive rotation, and controlled from the appropriate machine function control. A tripping finger 580 (Figures 7 and 17) is therefore arranged on the right hand end of shaft 581 which extends through the sleeve carrying the counter transfer drum and is connected through an intermediate gear of the actuator drive train. Regarding the 50 machine from the right side thereof, it will be observed that the actuator rotates in a counter-clockwise direction for addition. It will thus be seen that in additive rotation of the actuator the tripping finger 580 is rotated in a clockwise direction.

A trip slide 582 (Figures 7 and 17) is arranged to be vertically reciprocated by the trip finger 580 as the actuator approaches full cycle position and for pivotal oscillation by its control member 596 to bring it in and out of the path of the trip finger 580 by means of the lower pin and slot connection 533 through which it is supported on the machine frame. A spring 584 tensioned between the machine frame and the lower arm of 65 the member 582 tends to oscillate it in a clockwise direction and carries it out of the path of the trip finger. A locking member 585 pivoted at 586 has a laterally bent end portion 587 adapted to latch behind a tooth 588 of the trip slide 70 582 to retain such slide in an active position in the path of tooth 580 until the shift clutch is actuated. The tail 589 of the latch member cooperates with a cam 590 fixed to the shift clutch housing. On rotation of the shift clutch housing this 75

cam causes the latch member to be rotated in a clockwise direction, bringing the laterally bent end 587 against the cam face 581 of the trip slide and positively camming it out of the path of the tooth 580 to prevent a second actuation of the shift clutch. Spring 592 tensioned between the frame and the latch lever 585 tends normally to retain it in a position to engage the rear of tooth 588.

0 A control shaft 595, journaled in the side frame of the machine, carries a depending lever 596 having a laterally bent end portion 597 lying in contact with the lower forward edge of the trip slide 582. The lower end 597 of the lever 596, when moved rearwardly by means of the control shaft 595, moves the trip slide 582 into its effective position where it is held by member 585. This control shaft is oscillated at the proper time in the automatic computations hereinafter described to initiate carriage shifting.

The shift clutch trip slide 582 carries a pin 593 (Figures 7, 17, 18, and 20) adapted on reciprocation of the slide to operate one of the clutch control levers 566 and 566A, depending on the position of the shift clutch control interponent 576 which is pivoted at 576A to a strap 576B journaled on shaft 576C so that the said interponent is capable of horizontal movement to select one or the other clutch control levers for operation upon vertical movement of said interponent. A T-shaped head 576D on the interponent 576 is adapted in one position to overlie the tail 574A of the clutch control lever 566A and in its other position to overlie the tail 574 of the clutch control lever 566. The T-shaped head 576D is formed with a lateral extension which is adapted to be operated by pin 593 in either position of the interponent. Reciprocation of the shift clutch trip slide 582 therefore oscillates the head 576D of the interponent and the contiguous tail of one of the shift clutch control levers, depending upon the lateral adjustment of the interponent. One or the other of the shift clutches is thereby engaged for a cycle of operation, shifting the carriage one step to the right or left.

The means for effecting lateral adjustment of the interponent 576 to control the direction of this automatic shift comprises a manually operated lever 577 pivoted to the frame at 577A and having a lower portion lying adjacent and to the left of a vertical forward portion 576E of interponent 576. The shift control lever 577 is movable horizontally between stops 577B and a compression spring 577C disposed between the lever and a point on the frame tends to maintain it in either adjusted position.

A spring 576F, tensioned between the tail of interponent 576 and member 870 tends to move the head of the interponent to its position overlying control lever tail 574 and when the finger piece of the shift switch lever 577 is in its left-most position, it is free to do so. An automatic shift initiated while this adjustment is maintained operates the tail 574 oscillating lever 566 and engaging shift clutch 562 shifting the carriage one step to the right. When the shift switch lever is moved to its right hand position, however, the head of interponent 576 is moved to its position contiguous to control lever tail 574A. An automatic shift initiated while this adjustment is maintained will operate tail 574A oscillating lever 566A and engaging shift clutch 562A shifting the carriage one step to the left.

It will be noted that the directional adjustment of the shift clutch lever corresponds to the

direction of the denominational shift indicated by the relative movement of the counter indicator to the carriage as in the case of the shift key and not in the direction of the shift of the carriage.

As a safety factor to prevent damage to the machine in the event of misoperation of a portion of the clutch control mechanism, the slide 582 (Figure 17) has been made in two parts connected in slidable relation with one another by means of the pin and slot connections 583. They are normally held in their extended position by a compression spring 582A in such a manner that the compression spring takes the load applied at the top of the slide 582 by rotation of the tooth 580 and transmitted by the bottom portion of said slide to effect engagement of one of the shift clutches. Due to this two part construction it is evident that misoperation or a jam in the clutch control mechanism will merely result in a compression of spring 582A instead of a probably serious bending of the several parts.

Automatic division

Automatic division is performed in the present machine upon entry of the factors in the usual manner, positioning the carriage and shifting the division lever into its forward position whereupon a sequence of operations ensues which registers the quotient in the revolutions counter. Shifting of the division lever 600 starts the actuator in the subtractive direction and it acts to subtract the selected decimal multiple of the divisor from the dividend, registering the number of subtractions in the counter, until an overdraft occurs, which operates controls which effect a reversal of the actuator without effecting disengagement of the actuator clutch. The cycle immediately following upon the overdraft cycle therefore corrects the overdraft, and a control exerted during this cycle acts to disengage the actuator clutch in full cycle position, and to engage the carriage shift clutch for a single cycle. The carriage shift clutch, in terminating its cycle of operation, actuates controls to reengage the actuator clutch and again drive the actuator in a subtractive direction. This tour of operation repeats itself successively in consecutive denominational orders until the carriage reaches home position, when a special control intervenes to prevent engagement of the carriage shift clutch and all the mechanism is consequently brought to rest with all controls restored to their normal position.

The automatic division control lever 600 (Figure 11) is pivoted at 601 to the side wall of the machine and its upper end is brought toward the front of the machine to initiate a division operation. By this motion it moves the main division slide 602 and the supplemental division slide 603 toward the rear of the machine against the force of a spring 604 tensioned between the base of the machine and the main division slide. A short pin and slot connection 603A connects the supplemental division slide to the division lever so that this slide follows the movement of the division lever in both directions. The main division slide is, however, connected to the division lever by a longer pin and slot connection 602A.

This longer pin and slot connection 602A is so arranged that the main division slide will be pushed to the rear by a forward rocking of the division lever but will not be returned by the restoration of the division lever to inoperative position. A pair of latching pawls 605 and 606 are pivoted side by side on the side frame of the

machine at 601. The heads of both these pawls cooperate with a notch 602B in a widened portion of the main division slide into which they are pressed by their individual springs 608 and 609 5 compressed between the forward portion of the respective pawls and an extension of the side frame. By this means, the main division slide 602 is latched in the rear position to which it is forced by an operation of the division lever 600 10 until the two latching pawls 605 and 606 are concurrently raised.

Adjacent its rear end, the main division slide 602 has a camming bend 602C which cooperates with a notch in the shaft 615 to shift the shaft 15 laterally on a movement of the slide. Shifting of this shaft operates the shifting fork 616 (Figures 17 and 19) fixed adjacent its opposite end which controls the engagement of a clutch 617 for a purpose presently to be described.

20 Spaced from its rear end the main division slide 602 carries a laterally extending pin 613, the remote end of which lies directly in front of a vertical portion 227A (see Figure 2) of the link which controls the actuator reversing gear.

25 Rearward motion of the slide 602, then, serves to move the link 227 and place the gear control in position to cause subtractive rotation of the actuator.

Concurrently, the bell crank 223 (Figure 2) 30 attached to the forward end of link 227 is rocked, and the upper arm carrying roller 225 is moved downwardly, the roller being carried downwardly and toward the rear of the machine in the same manner as when actuated by the minus bar. In this motion it rocks control plate 120 (Figure 1) to cause engagement of the main actuator clutch 110. This mechanism is locked in this position for the duration of the division operation by the latches holding the 35 main division slide in its rearward position. The actuator, being thus set in motion, rotates continuously, subtracting the divisor or its decimal multiple from the dividend in the accumulator carriage at each successive rotation until an 40 overdraft occurs. In an overdraft operation, due to the tens carrying mechanism, all effective 45 numeral wheels to the left of those actuated are operated from their normal zero registration to a nine registration.

50 The movement of the familiar tens carrying mechanism of the machine in this operation is utilized to control the reversal of the actuator to effect a correction of the overdraft. This mechanism comprises carrying levers 425 (Figure 12) normally latched in their forward position as shown, but adapted to be tripped to and resiliently latched in their rearward position by the lug 426 of the numeral wheel in a direct transit from zero to nine. Abutting directly 55 behind the carry lever 425 of the numeral wheel cooperating with the next to the last carrying order of the actuator toward the left, is a lever 630 (see also Figure 16) pivoted to the machine frame at 631. The pivot 631 permits movement 60 of the lever 630 in a vertical plane when a carry lever 425 is tripped. Pivoted for movement in a horizontal plane to the end of the lever at 632 is a bifurcated tail piece 633. This tail piece is 65 movable on its pivot by means under control of the main division slide presently to be described in connection with the means for terminating the additive corrective operation, and in its operative position overlies the foot 634 of a vertical lever 635 pivoted at 636 (see also Figure 3), on a 70 second lever 637 which is pivoted to the machine 75

frame at 631. Pivoted to the lever 637 at 638 is a depending link 639, the lower end of which engages one arm of a bell crank 640 pivoted to a standard 641 on the machine frame. The upper arm of the bell crank 640 operates against a collar 642 on the shaft 135 in such a manner that rocking of the bell crank brought about by downward pressure on link 639 shifts the shaft 135 so that it carries its pin 134 into engagement with the gear 131 which serves to drive the actuator 10 in the additive direction. This shift is positively brought about by means driven from the actuator and controlled by the numeral wheels in an over-draft operation.

In an overdraft operation the carrying lever 15 425 of the controlling denominational order is rocked to the rear carrying with it the lever 630 and depressing its tail piece 633. This depresses the foot 634 of the vertical lever 635, rocking said lever against the pressure of spring 635A to de- 20 press a pin 645 slidably arranged in a socket in the upper end of lever 637 and arranged to be retained in either of the two adjusted positions by a spring pressed ball indicated at 646. These operations occur just before the actuator 25 reaches its full cycle position and their result is to project the end of pin 645 into a position where it will be engaged by a specially formed cam face 647 on a plate 648 (see Figure 12), fixed on the left end of the actuator shaft. This engagement 30 taking place while the actuator is still under drive in the negative direction drives the system including lever 637, link 639, bellcrank 640, and shaft 135, to positively carry the pin 134 out of its seat in gear 132 and into its seat in gear 131 35 just as the actuator reaches full cycle position and against the force of spring 142 which is compressed in this operation, rendering unnecessary a release of link 227 which normally controls the position of pin 134, and also controls the main 40 actuator clutch. Thus the actuator is reversed without disengaging the main clutch and enters upon an additive cycle.

Pressure on the linkage system above outlined is at once relieved upon reversal of the actuator but a reseating of the pin 134 in the gear 132 under pressure of spring 142 is prevented by the displacement of the seats and reversal in half cycle position is prevented by the mechanism shown in Figure 4 and described hereinbefore. 45 At the end of a single cycle of additive rotation the actuator is arrested in full cycle position by disengagement of the main clutch and spring 142 is permitted to reseat pin 134 in its seat in gear 50 132.

Means are provided whereby the tail piece 633 (Figures 3 and 16) normally held in inoperative position as shown, is rocked to operative position overlying the tail 634 upon an operative stroke of the automatic division lever 600. This is controlled by a lever 650 doubly pivoted for universal movement at 651 the upper end of which is disposed between the bifurcated end of a tail piece 633. A spring 652, tensioned between the upper portion of this lever 650 and a vertical portion 653A of a slide 653, holds the upper portion of the lever 650 against the vertical portion 653A of the slide 653 in such a manner that the upper portion of lever 650 follows the movement of the slide 653. The lever 650, and consequently the tail piece 633, are normally maintained in inoperative position by a spring 653B which urges the slide 653 to the left as shown in Figure 3. The opposite end of the slide 653 is provided with a cam face 653C (see also

Figure 10A) which when the slide 653 is in in-operative position lies in the path of a depending arm 602E of the main division slide 602. It is obvious, then, upon rocking the automatic division lever 650 to its operative position, the rearward movement is such that the main division slide 602 thereby will, through the depending arm 602E, cam the slide 653 to the right as shown in Figure 3, and move the lever 650 and consequently the tail piece 633 into operative position.

As indicated in dotted lines in Figure 12, the actuator disk of next lower order from that carrying the cam surfaces 657 and 658 is notched to permit transverse movement of lever 650 from operative to inoperative position. Means are provided to insure positioning of the lever 650 in either operative or inoperative position upon rotation of the actuator. A plate 650B (Figures 12 and 16) secured to the shaft 161 is provided with two notches intermediate exterior limiting arms formed thereon, said lever 650 being aligned with the respective notches when in operative and inoperative position. Intermediate the two notches a beveled point is provided to positively cam the lever 650 to one or the other side of the notched actuator disk in the event that the nose of said lever is positioned in the notch in said disk upon rotation thereof. The left hand notch in plate 650B as viewed from the right in Figure 16 is of greater depth to permit oscillation of lever 650 when in operative position by means to be described hereinafter, and said notch serves as a guide for said lever in the rearward oscillation thereof.

In its operation position the lever 650 is arranged to effect a temporary disengagement of the main clutch at the end of an additive rotation of the actuator caused by an overdraft registration. To accomplish this, the upper portion of the lever 650 lies in the path of a cam 656 (see also Figure 13) carried on one of the actuator segments. The end of the camming member which approaches the lever during subtractive rotation of the actuator, carries a side bevel 657 which acts to move the lever 650 aside without tripping it, but the end which approaches the lever in additive rotation of the actuator carries a cam face 658 which acts to rock the lever 650 about its vertical pivot lifting its tail 659. This tail underlies and thus acts to lift one end of a double lever system 660 (Figure 3) expediently pivoted in the machine, the other end of which lies in an aperture in the rearward end of the actuator clutch control link 121. The lift exerted on the one end of the double lever system 660 causes a corresponding lift at the other end, raising the clutch control link 121 clear of pin 119 on the actuator clutch control bell crank 115. Thus released, the bell crank 115 at once contacts the clutch housing 112 under urge of spring 118, and as the clutch reaches full cycle position the foot 117 enters the aperture in the clutch housing and disengages the clutch, locking the actuator in full cycle position. During the additive rotation just completed, a cam 648A (Figure 12) formed on plate 648 acts to restore pin 645 to its normal inoperative position.

Automatic add-key release

As mentioned hereinbefore, proper functioning of the automatic division mechanism is impossible while the add key 250 (Figure 10) is maintained in its depressed position. Therefore means have been provided for automatically re-

leasing said depressed add key, said release being controlled by the rocking of the automatic division lever 650 to its operative position. This is accomplished by means of a horizontal slide 275 (Figure 10) slidably supported in the machine by pin and slot connections 276, the forward end of which is provided with a cam face 275B which lies immediately to the rear of a laterally projecting pin 250A on the lower extremity of the add key 250 in such a manner that a forward movement of said slide will result in a clockwise oscillation of said depressed key about its pivot point 251, thereby releasing the notch 255 from the supporting plate and permitting the cam face 275B to force the pin 250A and consequently the key to its elevated position. The slide then being held underneath the pin prevents depression of the key during the course of a division operation. The necessary forward movement of the slide 275 is effected through the counterclockwise oscillation of a bell crank 277 (Figure 10A) pivotally mounted on the machine base at 278, one arm of which is disposed immediately to the rear and in contact with a depending portion 275A of the slide 275. The other arm of the bell crank 277 is provided with a camming face 277A disposed in the path of the depending portion 602E of the main automatic division slide 602. It is obvious that a rearward movement of the main division slide 602 will initiate a problem in automatic division will result in a rocking of the bell crank 277, thereby releasing the add key in the manner described above.

Automatic control of carriage shift during division

Means are provided for automatically engaging the proper carriage shift clutch upon disengagement of the main actuator clutch. Since in automatic division the direction of carriage shift must always be from right to left, means are provided under control of the main division slide 602 for moving the selecting interponent 576 over clutch lever tail 574A, regardless of the adjustment of shift control lever 577. As hereinbefore set forth, the positioning of main division slide 602 (Figures 10 and 19) shifts shaft 615 to move shifting fork 616 into position to engage the restart clutch 617. The shifting fork 616 is provided with a depending portion 616A (Figure 17) lying adjacent the left side of an upstanding portion 576G of the interponent 576. But, upon a setting of the main division slide, the rear end of interponent 576 will be moved to its right hand position overlying clutch lever tail 574 and each subsequent reciprocation of trip slide 582 will cause engagement of the clutch 552A, shifting the carriage one step to the left.

Means are provided whereby the trip slide 582 is reciprocated automatically upon disengagement of the main actuator clutch. A lever 673 (Figure 5) pivoted at 671 on a rigid member dependent from the carriage track has an angular tail portion 672 overlying the clutch control link 121 and a nose overlying rocking pawl 605 and the nose 674 of a lever 673 on control shaft 595 (see also Figure 10). It will be noted in Figure 10 that although the nose 674, slidably mounted on the lever 673 and controlled by the bell crank 615, is normally held out of the path of the lever 673 by a spring 675C, means are provided whereby movement of the supplementary division slide 603 to operative position will, through its lateral extension 603B riding the cam 75

face 675B, rock said bell crank 675 counter-clockwise, thereby positioning said nose 674 to underlie the lever 670. When the control link 121 (Figure 1) is raised to arrest the actuator at the end 5 of a corrective additive rotation, the pawl 670 is rocked clockwise and its nose depresses lever 673 rocking control shaft 595 to trip the automatic carriage shift control mechanism hereinbefore set forth.

10 Toward the end of the cycle of operation of the carriage shift clutch 562A, cam 680 (Figure 17), rigid with cam 561A driven by said clutch, rocks its cooperating arm 681 to reengage the main clutch. This arm is journaled on a shaft 15 682 on the opposite end of which is fixed an arm 683 underlying the pin 684 (Figure 1) on the actuator clutch control bell crank 115. Movement of the arm 681 is normally ineffective, but a setting of the main division slide 602 operates 20 shifting fork 618 moving the clutch member 617 (Figures 5 and 19) into engagement with a complementary clutch face 617B, fixed to arm 681 and clutches it to the shaft so that when it is rocked by cam 680 the clutch bell crank 115 will 25 be rocked to reengage the actuator clutch. Said clutch bell crank 115 is then latched by the reengagement of the pin 119 in the notched end of control link 121. This tour of operations is repeated in each denominational order until the 30 carriage reaches its extreme left hand position.

Means are provided for terminating the calculation at the end of a tour of operations if the carriage is in its extreme left hand position. Pawl 690 (Figure 5) pivoted at 691 has a nose 35 overlying both latches 605 and 606 which it trips concurrently, completely releasing the main division slide 602 so that it may be returned to inoperative position by its spring 604 to terminate a calculation. A link 692 connects the tail 40 of lever 690 with one end of a finger 693 pivoted at 694 and positioned to project through an aperture in the carriage track into contact with the underside of the carriage, in which direction it is urged by spring 695. The aperture is so 45 positioned that the carriage covers it and blocks the rise of the finger except when the carriage is in its extreme left hand position. The lower end of the finger also carries a pivoted latch 696 which projects through a slot in plate 697 depending from the lower side of the carriage track 600 and is urged into latching position against the lower end of said slot by a spring 698 tensioned between an intermediate portion of the latch and a depending plate 697.

55 The nose of the latch overlies the actuator clutch control link 121 and is therefore raised at the conclusion of each corrective additive rotation when the actuator clutch is disengaged. If the carriage is out of its extreme left hand 60 position, the finger 693 is unable to rise under urge of spring 695 and the latch therefore merely falls back without effect. If, however, the carriage is in its extreme left hand position, the spring moves the finger through the aperture and 65 concurrently moves link 692 to the right, rocking lever 698 and depressing the underlying tails of latches 605 and 606, thus completely releasing the main division slide 602, which returns to its inoperative position terminating the calculation. 70 The carriage shift trip slide 582 is, as usual, tripped to its operative position by lever 670 but is returned to inoperative position (see Figure 7) before being actuated by the action of cam face 602D on the main division slide 602 75 which depresses pin 622 on the trip slide latch-

ing member 585, depressing this lever and positively camming the slide 582 to its inoperative position.

Manually controlled means are provided for terminating a calculation prior to its completion. 5 The calculation may be terminated at the conclusion of the tour of operation in any denominational order by manual return of the division lever 600 to its inoperative position at any time during the tour of operations. This carries 10 the supplementary division slide 603 (Figure 11) to its forward position and a cam face 603C formed thereon acts on a lug 606A formed on a latch member 606 to release said latch from the notch 602B in the main division slide. The 15 main division slide is, however, maintained in its operative position by latch 605 until the end of the tour of operations when it is tripped by the rocking of the overlying lever 670 the tail of which overlies actuator clutch control link 121. Tripping of latch 605 completes the release of the main division slide 602 permitting it to return to inoperative position and terminating the calculation. 20

The second latch 605 may be alternatively released by manually operated means under the control of the multiplier clear key to terminate the calculation at the end of any cycle of the actuator and before completion of a tour of operations. The stem of the multiplier clear key 30 is provided with a pin 625 (Figure 11) overlying one end of a lever 626 pivoted to the side wall of the machine at 627. The other end of this lever has a laterally bent portion 626A lying in a wide notch in latch 605. Depression of the 35 multiplier clear key rocks the lever 626, raising latch 605 and provided latch 606 has been released by return of lever 600, this action will completely release slide 602, terminating the calculation. This last releasing means of the latch 40 605 is only used, however, when the machine has been misoperated, as when the division lever has been pulled while no factors are set in the machine, in which case it operates continuously in the subtractive direction, and no other means 45 is effective to arrest it.

Complementary quotient arresting mechanism

Means have been provided whereby the automatic division mechanism will be arrested by the 50 subsequent carriage shift following the completion of the cycle of operations in each denominational order of the calculation in the event that the machine has been set to register a complimentary quotient. This is accomplished 55 through means of a member 610 (Figures 3, 11 and 17) which is slidably and rotatably supported in the machine at its lower end by pin and slot connection 610A and provided on its upper end with a horizontal portion, which is held by 60 spring 610C in contact with the edge of a second member 611 against which it slides during an operation. The member 611 is pivotally mounted at 611A and by its contact with the periphery of the reversing shaft 151 is adapted to 65 normally hold the horizontal portion of the member 610 out of operative position. As described hereinbefore, the shaft 151 is shifted laterally to effect a reversal of the counter actuator so 70 that it will rotate in the same direction or in the opposite direction from the accumulator actuator. As seen in Figure 3, a shift of the shaft 151 to the left will result in its rotating in the same direction as the accumulator actuator, 75

- which, in the present instance, will effect registration of a complementary quotient.
- Spaced from one of its ends, the shaft 151 is provided with a depression 151A into which the rear edge of the member 611 will be disposed when said shaft is shifted to its extreme left or complementary quotient position. The slot 151A of shaft 151 is provided with a gradual approach so that a shift of shaft 151 to its extreme left position results in a counter-clockwise rotation of the member 611 (Figure 17) about its pivot 611A, thereby permitting spring 610C to move the horizontal portion of the member 610 into operative position. In its operative position the horizontal portion of the member 610 is sufficiently near the hooked end 582B of the carriage shift slide 582 so that when said shift slide is rocked counter-clockwise into engagement with the rotating tooth 580 to initiate a carriage shift, as hereinbefore described, the hooked end 582B will be rocked into a position overlying the horizontal portion of the member 610, and the subsequent downward movement of the slide 582 will result in a similar downward movement of the member 610.
- The lower portion of the member 610 is provided with a lateral extension 610B, overlying the latches 605 and 606 so that said downward movement of the member 610 will depress the tails of said latches, thereby effecting a release of the main division slide 602 and terminating the calculating operation after its completion in one denominational order. However, it is obvious that if the operator intended to obtain registration of a complementary quotient, he may do so through continuous operation by merely holding the automatic division lever 600 in its forward operative position, thereby preventing the slide 602 from returning to effect termination of the calculating operation.
- Warning bell mechanism**
- The present machine is provided with a mechanism for signaling to the operator when the capacity of the calculating mechanism is exceeded in addition, subtraction, and multiplication. The signaling means is, however, disabled during automatic division and its control mechanism used as a machine function control in that operation.
- A bell 450 (Figures 3 and 12) suitably mounted on the side frame is arranged to be sounded by a clapper 451 pivoted to a standard on the machine base and urged to a neutral position by spring 453. A vertical shoulder push link 454 extending through a slotted lug on the clapper arm constitutes the operating means therefor. The extension 633A of the tail piece 633 of the division reverse control mechanism overlies the upper end of link 454. This tail piece 633 is pivoted at its forward end to the vertically pivoted overcarry lever 630, the forward crosshead of which lies behind the carry levers 425 cooperating with the last three orders of the actuator. When the extension 633A of the tail piece 633 is in position overlying the link 454 where it will be during any problem other than automatic division, an overdraft, or the rocking of the numeral wheels of the accumulator carriage from zero to nine, will result, through the tooth 426 rocking the transfer lever 425 and tail piece 633 in a downward reciprocation of the link 454. The bell clapper 451 is therefore oscillated, ringing the bell, indicating that a transferred increment has been lost and that the indicated registration is therefore incorrect.

In automatic division operations, however, the tail piece 633 (see also Figure 16) is moved so that its other arm overlies the foot 634 and its extension 633A is consequently moved from its position overlying the link 454, thereby rendering the throwing of the transfer lever 425 ineffective to sound the alarm mechanism during that operation.

Automatic multiplication

The calculating machine as shown in the patent to Friden Number 1,643,710, is provided with a trip slide for tripping or raising the rear end of the latch lever 121 to release the clutch control lever 115 at the end of a selected, predetermined number of rotations of the actuator. Movement of the trip slide 700 serves to raise the rear end of the latch lever 121 and the trip slide is moved by a pin 711 (Figure 10) carried by the slide bar 710, which is positioned in variable angular positions, depending upon the predetermined number of rotations of the actuator, by the lever 720, which is provided with a pin 721 engaging in a slot 712 in the slide bar 710. The slide bar 710 is connected to a rack as disclosed in said patent which is restrained against movement by a spring, and which is given a step by step movement by a tooth integral with the actuator clutch. The slide bar 710 which carries the pin 711 therefore is moved one step for each rotation of the actuator and, by variably positioning the slide bar 710, a different number of steps of movement are required before the pin 711 comes into engagement with the stepped face of the slide plate 700. The next rotation of the actuator after such engagement causes the pin 711 to move the slide plate 700, and thereby disconnect the latch bar 121 from the clutch control lever 115.

The slide bar 710 is normally held in depressed position by the spring 722 connected to the lever 720 which is in turn connected to the slide bar 710. When the slide bar 710 is in its normal depressed position, the pin 711 is in zero position, that is, one station below the number one position, in which zero position it is shown in Figure 10. With the pin 711 in this zero position, it may oscillate through one step of movement, moving the slide 700 for less than a full step as set forth in the above-mentioned patent, thus preventing operation of the trip slide latch.

As can be seen in the Friden Patent Number 1,643,710, the unit is provided with a series of keys ranging in value from one to nine, which serve to position the pin 711 to automatically control the number of revolutions of the actuator. Depression of the key valued eight, for instance, will position the pin 711 in front of the eighth step on the slide plate 700, so that at the end of the eighth rotation of the actuator the clutch control link 121 will be raised and the clutch disengaged, thereby terminating the operation.

Control of carriage shift during automatic multiplication

Depression of a multiplier key therefore results in the rotation of the accumulator actuator the number of times delineated on said key, during the last rotation of which the plate 100 (Figure 10) is moved to the rear by pin 711 to actuate instrumentalities for terminating the calculation. It is at this point in the operation that it is desired to initiate action of the shift clutch. For this purpose a member 760 is provided. Said

member is pivoted to the plate 700 at 761 and abuts at the rear end thereof a laterally bent portion 762 of a lever 763, depending from the control shaft 585. Rearward motion of the plate 700 will impart a counter-clockwise oscillation to the control shaft 585, rocking lever 596 (Figure 7) carried on its opposite end and tripping slide 582 into operating relation relative to tooth 580. As the actuator reaches full cycle position, this tooth 580 contacts the upper end of slide 582 depressing the slide and its pin 593 to raise the selected shift clutch control arm and engage said clutch. As the clutch starts, cam 590 rocks the latch member 583 camming the slide 582 out from under the arrested tooth 580 and releases the clutch control arm 586 so that the shift clutch will be disengaged and arrested in full cycle position at the end of a single rotation. Upon operation of the carriage shifting mechanism, means controlled thereby act to effect a release of the depressed multiplier key. This portion of the mechanism is fully described in the copending application of Avery and Lerch, Serial Number 405,127, filed November 6, 1929.

Means are provided under control of the add key 258 for disabling this shift clutch control when said key is depressed. This key 258 is maintained in depressed position during straight adding and subtracting operations and acts to release the keyboard setup and to limit the rotation of the actuator to a single cycle in either direction unless a multiplier key is depressed to perform multiple additions for adding a certain number to the registered sum a plurality of times. For this purpose a link 257 (Figure 10) is attached to the lever 252 and has a foot 258 extending under pin 721 of the multiplier pin adjusting mechanism. Depression of the key 258 raises this link slightly, bringing pin 721 into contact with the one step of plate 700 so that the plate will be moved during the first rotation of the actuator to cause disengagement of the actuator clutch. To prevent undesirable operation of the automatic carriage shift during the performance of multiple addition, a second link 259 is provided which is adapted to connect the rear end of lever 252 with an intermediate portion of the member 760. Raising of the rear end of lever 252 incident to the depression of the key 258 thus raises the rear end of member 760 so that when it is moved to the rear with plate 700, it will overshoot the laterally bent end 762 of lever 763 so that the shift clutch is not effected by such rearward movement.

Since the carriage shifting mechanism, which normally effects release of a depressed multiplier key during a multiplication operation, is disabled during depression of the add key 258, it is necessary to provide an alternative means for releasing the multiplier key which may be used for effecting repeated addition while the add key is depressed as described above. The lever 760, which is rocked by depression of the add key, to disable the multiplier carriage shifting control, has a hooked front end 786D, adapted to engage over a stud 786C carried by the multiplier key latching bar, which is not shown. When the key 258 is depressed, disabling the carriage shift control and consequently rendering the normal multiplier key releasing means ineffective, the hook 786D engages over the stud 786C and carries the multiplier key latching slide to the rear with plate 700, thereby releasing the depressed multiplier key.

Non-shift key

In certain calculating operations, it may be desirable to use the automatic multiplication mechanism without the automatic shift feature. For this purpose a special non-shift key 770 (Figure 10) has been provided. This is slidably and pivotally mounted by a slot and stud connection 770A and is provided with a notch 770B adapted to engage the upper supporting plate, and a spring 770C for retaining it in depressed position. The lower end of the key stem lies directly over the end of the lever 760, the operation of which has been described hereinbefore. It is evident that depression of the non-shift key 770 will rock the lever 760 about its pivot point 761, thereby disabling the carriage shifting mechanism during automatic multiplication operations in the manner described.

Power control and interlocks

Means are provided for controlling the circuit of the driving motor to effect closure thereof, only when one of the several machine controls is functioning. Two normally open, spring braced contacts 800 (Figure 1) are connected in series in the motor circuit, and are mounted in a suitable insulating block fixed to shaft 801 journaled in the frame. Clockwise oscillation of shaft 801 is adapted to bring the near contact blade against abutment 802 to effect a closure of the contact. One means for producing this oscillation of the shaft comprises a lever 803 fixed to one end thereof and connected by a push link 804 and stud 805 to a lever 806. The lever 806 which is fixed to the shaft 807 journaled in the machine, lies directly behind and in contact with clutch control bell crank 115 so that a rocking of this bell crank to cause engagement of the actuator clutch will rock lever 806 rearwardly to effect closure of the circuit through the linkage just described.

A second means for operating the contact comprises a lever 810 (Figures 8 and 18) pivoted to the frame at 811 and supported by spring 812. One end of this lever has a perforated angular portion 813 which receives an angled end of shaft 801, while the other end is provided with a foot 814 underlying arm 815 fixed on one end of shaft 820. This shaft 820 supports four members, any one of which may be operated to initiate a machine function, the accumulator clear clutch bell crank, the counter clear clutch bell crank, and the shift clutch power control levers 838 and 838A. Each of these is journaled on the shaft 820 and carries a projection 831, extending into a wider key way in the shaft, so that oscillation of any of these members will effect rotation of the shaft without actuating the other members journaled thereon. Oscillation of shaft 820, by this means, depresses arm 815 and foot 814 rocking shaft 807 in the proper direction to effect closure of the contacts.

Arm 815 is provided with a hooked extension 815A which, when said arm is in its depressed position, lies in the path of a lateral portion 816A of the lever 816 fixed to the shaft 807 so that it blocks oscillation of shaft 807 and prevents actuation of the actuator clutch bell crank 115. Conversely, when the actuator clutch bell crank is rocked to engage the clutch, the shaft 807 is rocked, bringing the lateral portion 816A of the lever 816 into contact with the underside of extension 815A of lever 815, thereby blocking oscillation of shaft 820. It will be noted that the

construction of the levers 815 and 816 in this connection is such that the least movement of either completely blocks the movement of the other. This effects an interlock between the clear and shift keys and the main actuator clutch so that neither can be operated while the other is in operation. Disposed immediately to the rear and in contact with the pins 568 and 569A of the carriage shift control keys 570 and 570A are a pair 5 of shift clutch power control levers 830 and 830A (Figure 6) which are oscillated to the rear upon depression of either shift clutch key thereby rotating the shaft 820 to effect closure of the electrical contact. After the contact is made, it is 10 maintained during the remainder of the cycle of operation of the shift clutch through means of an extension 832 of arm 810 (see also Figure 8) which underlies the tails 574 and 574A of the shift clutch bell crank, which keeps the lever 818 15 in its depressed position until said bell cranks are again rocked to effect disengagement of the clutch. This means is also effective in maintaining the circuit closed during the shifting operation in automatic multiplication operations; however, in automatic division operations the contacts are maintained closed throughout the computation by the cam end 602H of the main division slide which rides over the foot 814 of the contact control lever 810 and maintains it in 20 depressed position throughout the operation.

A lock is provided to prevent engagement of the main clutch while either shift clutch is functioning, comprising an arm 860 pivotally mounted on lever 885 at 861 and supported by spring 862 (see Figure 8). Lever 885 is depressed throughout the operation of either shift clutch by the cam 898 thereby carrying the lug 863 on arm 860 against a square stud 864 carried on arm 815, rocking the said arm down to block the lever 816 as described in a previous operation, thereby locking the actuator clutch.

During division operations, the restart of the actuator clutch must be accomplished somewhat before the shift clutch reaches home position. For this purpose a plate 865 (Figure 11) is positioned on the main division slide 602 so as to ride 45 against arm 860 when the slide is operatively positioned, forcing the lug 863 to the rear of square stud 864, thereby disabling the lock.

An interlock is provided to prevent operation of either shift control lever while the other shift clutch is operating, comprising a plate 870 (Figures 6 and 6A) pivoted at 871 and provided with shoulders 872 and 873 underlying control lever 50 tail 574 and 574A, respectively. The tail 574 is provided with a cam surface 874 which, on operation of a lever, rides against shoulder 872, moving plate 870 to a position where its shoulder 873 underlies the end of tail 574A, preventing its operation. Conversely, operation of lever 866A places 55 a portion of the tail 574A behind the shoulder 873, preventing pivotal motion of plate 870 and blocking descent of tail 574 to prevent operation of its clutch.

An interlock is provided between the clearing keys and the zero multiplier or automatic carriage shift control keys, to permit concurrent operation of the two clearing keys, but to lock 60 the shift keys by the operation of either clear key and conversely to lock both clearing keys upon operation of either shift key. A locking

plate 850 is pivoted beneath the four keys (see Figure 9) between the side frame and a fixed plate and its edges 851 underlying cam surfaces 852 of the clear keys 475 and an edge 853, adjacent edges 854 of the shift keys. The spring 855 5 tends to hold the plate in vertical position as shown in Figure 8. Depression of either of the clear keys 450 or 475 will rock the plate 850, carrying the edge 853 under the body of keys 570 and 570A and thus prevent depression of the shift keys while the depression of either shift key will prevent rocking of plate 850 and thus lock both clear keys against depression.

A set of locking arms 840 fixed on shaft 841 (Figure 2) are operable through arm 842 by a 15 cam 843 on the actuator shaft to lock the selection in the drum while it is out of full cycle position. Means are also provided for actuating this locking means whenever an automatic operating bar or multiplier key is depressed. A link 20 844 connects an extension of one of the locking arms 840 with a gate 845 pivoted at 846. Carried on a downward extension 847 (Figure 9) of gate 845 is a stud 848, over which lies the notched rear end of a link 849 connected at its forward end to 25 the control plate. Depression of an operating key rocks this plate as hereinbefore set forth, rocking the gate and moving the locking arm 840 to locking position. An extension 856 of the locking plate 850 (Figures 1 and 9) lies directly behind 30 gate 845, so that rocking of the gate also rocks plate 850, locking both shift keys against operation.

We claim:

1. In a calculating machine, division mechanism including operation initiating means, counting mechanism, a control member for determining positive or negative registration of the quotient thereon, and means controlled by said member for restoring said means to inoperative position.

2. In a calculating machine, division mechanism including an adjustable control member for initiating operation thereof, means for latching said member in operative position, counting mechanism, control means for determining positive or negative registration of the quotient thereon, and means controlled by said control means for disabling said latching means.

3. In a calculating machine, division mechanism including an adjustable control member for initiating operation thereof, means for latching said member in operative position, counting mechanism, control means for determining positive or negative registration of the quotient thereon, and means controlled by said control means for interrupting operation of said mechanism after registration in one order, said last named means being adapted to permit registration of a plural figure quotient with said member manually held in operative position.

4. In a calculating machine, division mechanism including an adjustable control member for initiating operation thereof, means for latching said member in operative position, a separately settable element, and means controlled by said element for interrupting operation of said mechanism after determination of one quotient digit.
